MASS SPECTROMETER

William C. Wiley, Detroit, Mich., assignor to Bendix Aviation Corporation, Detroit, Mich., a corporation of Delaware

Application January 28, 1954, Serial No. 406,746

10 Claims. (Cl. 250—41.9)

This application is a continuation in part of copending application Serial No. 325,082 filed December 10, 1952, by William C. Wiley and now abandoned.

This invention relates to mass spectrometers, and more particularly to mass spectrometers for producing relatively strong and clear indications as to the masses of different ions.

Some mass spectrometers utilize pulses of ions to determine the masses of the different gases or vapors in an unknown mixture and the relative abundance of each gas and vapor in the mixture. In these spectrometers, ions are formed from the molecules of gas and vapor and are accelerated by a force to produce a movement of the ions through a predetermined distance. The ions of relatively light mass have a greater velocity imparted to them by the force than the ions of heavy mass, thereby travelling through the predetermined distance before the ions of heavy mass. By measuring the relative times at which the ions of different mass travel through the predetermined distance, the masses of the ions can be determined.

Since the ions are moving in pulse form, the number of ions in each pulse is relatively limited. This causes signals of relatively weak strength to be produced by the ions after their movement through the predetermined distance. Because of the relative weakness of the signals, amplifiers are employed to increase the strength of the signals so that clear indications of the ion masses can be obtained.

In some time-of-flight mass spectrometers now in use, electronic amplifiers are employed to increase the strength of the output signals. These amplifiers are fairly expensive because they must have a large gain and a sensitive response over a wide range of frequencies. Other mass spectrometers now in use employ electron multipliers to increase the strength of the output signals. Such multipliers have not been entirely successful since they require a large amount of space to produce a satisfactory gain in signal strength. Because of their excessive size, the electron multipliers now used in time-of-flight mass spectrometers are also heavy and costly.

This invention provides a mass spectrometer which amplifies the output signals from the spectrometer simply, efficiently and inexpensively. The amplification is provided by an electron multiplier having a first plurality of plates for collecting different lateral portions of each ion pulse. Each plate in the first plurality produces a number of electrons proportional to the number of ions collected by the plate and directs these electrons towards successive plates in the plurality. The electron multiplier also includes a second plurality of plates, a first one of which receives electrons from the first plurality of plates and produces a proportionately increased number of electrons. Each of the other plates in the second plurality receives electrons from a preceding plate in the plurality and produces a proportionately increased number of electrons. The output signals from the spectrometer are obtained by collecting the electrons emitted by the last plate in the second plurality.

2

An object of this invention is to provide a mass spectrometer for producing a pulse of ions and for imposing a force on the ions to produce a separation of the ions on the basis of their mass during their travel through a predetermined distance.

Another object is to provide a mass spectrometer of the above character for determining the masses of the different ions in a pulse by measuring the time required for the ions to travel through a predetermined distance.

10 A further object is to provide a time-of-flight mass spectrometer of the above character which includes an amplifying system for simply and efficiently producing a considerably increased gain in the signal produced by the ions after their travel through the predetermined distance.

15 Still another object is to provide a time-of-flight mass spectrometer of the above character utilizing an electron multiplier of relatively small size and weight to considerably amplify the output signals produced by the ions.

20 A still further object is to provide a mass spectrometer of the above character which includes an electron multiplier so constructed as to receive ion pulses of relatively large width and to amplify without any material distortion the signals produced by the ions in each pulse.

25 Other objects and advantages will be apparent from a detailed description of the invention and from the appended drawings and claims.

In the drawings:

Figure 1 is a somewhat schematic view, partly in block form and partly in perspective, illustrating the electrical and mechanical features constituting one embodiment of the invention;

Figure 2 is an enlarged perspective view illustrating in detail one embodiment of an electron multiplier forming a part of the mass spectrometer shown in Figure 1, certain 35 members being broken away to indicate other members more clearly; and

Figure 3 is an enlarged, simplified plan view of the embodiment of the electron multiplier shown in Figure 2 and schematically illustrates the operation of the multiplier.

40 In one embodiment of the invention, a wedge-shaped filament 10 made from a suitable material such as tungsten is provided. An electrode 12 is disposed at a relatively close distance to the filament 10, such as 2 millimeters, and is provided with a vertical slot 14, the intermediate position of which is at substantially the same vertical level as the filament 10. An electrode 16 having a slot 18 corresponding substantially in shape and position to the slot 14 is separated from the electrode 12 by a relatively small distance, such as 2 millimeters, and is in substantially parallel relationship to the electrode. A collector 20 is positioned at a relatively great distance from the electrode 16 and in substantially parallel relationship to the electrode.

45 55 A backing plate 22 is disposed in substantially perpendicular relationship to the electrode 16 and the collector 20 at an intermediate position between the electrode and the collector. The plate 22 is positioned slightly to the rear of an imaginary line extending from the tip of the filament 10 through the slots 14 and 18 to the collector 20.

60 An electrode 24 is separated from the backing plate 22 by a relatively small distance, such as 2 millimeters, so as to be positioned slightly in front of the imaginary line disclosed above. The electrode is disposed in substantially parallel relationship with the backing plate 22 and is provided with a horizontal slot 26.

65 70 Top and bottom slats 28 extend from the backing plate 22 to the electrode 24 to form a compartment with the electrode 16 and the collector 20. A horizontal slot 30 is provided in the bottom slot 28 at a position directly below the imaginary line disclosed above. A conduit 32 communicates at one end with the slot 30 and at the other

end with a receptacle 34 adapted to hold the molecules of the different gases and vapors in an unknown mixture.

An electrode 36 having a slot 38 corresponding substantially in shape and position to the slot 26 is disposed at a relatively small distance, such as 2 millimeters, in front of the electrode 26. An electrode 40 is positioned at a relatively great distance, such as 40 centimeters, from the electrode 36 and in substantially parallel relationship to the electrode 36. The electrode 40 is provided with a slot 42 corresponding in position to the slot 38 but slightly larger in its dimensions than the slot 38. The slot 42 is covered by a suitable wire mesh. The electrode 40 is provided at its left extremity with an auxiliary portion 43 which is slightly to the rear of the main portion of the electrode and substantially in parallel with such main portion.

An electron multiplier 44 is disposed at a moderate distance, such as 2 centimeters, in front of the electrode 40 to receive the ions passing through the slot 42. Although the electron multiplier may be considered as including the electrode 40, the electrode is shown separately in Figure 1 for purposes of providing clarity in the disclosure of the operation of the mass spectrometer. As will be disclosed in detail hereinafter, the electron multiplier 44 has a plurality of plates to produce a considerable gain in the signals which are formed when the ions reach the electron multiplier. A time indicator, such as an oscilloscope 46, is connected to an output terminal of the electron multiplier to show the relative times at which the ions of different mass reach the electron multiplier. An input terminal of the oscilloscope 46 is also connected to an output terminal of a pulse forming circuit 47 such that the sweep of the oscilloscope beam is initiated by a pulse from the circuit 47.

The electrode 12 normally has a positive voltage applied to it through a resistance 48 from a suitable power supply 50. A positive voltage of relatively low magnitude is applied to the collector 20 through a resistance 52 so that the collector will attract electrons flowing through the slot 18 and electrons secondarily emitted from it by the impingement of the electrons from the filament 10. The filament 10, the backing plate 22 and the electrode 24 are connected to grounded resistances 54, 56 and 58, respectively, so as to be substantially at ground in the steady state operation. The electrodes 16, 36, and 40 are directly grounded.

The electrons emitted by the filament 10 are attracted towards the electrode 12 because of the positive voltage on the electrode 12 with respect to the voltage on the filament. In the steady state operation, the electrons are decelerated in the region between the electrodes 12 and 16 since the electrode 16 is at a lower potential than the electrode 12. This prevents any electrons from traveling into the region between the backing plate 22 and the electrode 24 to ionize molecules of gas or vapor introduced into the region.

At predetermined times, negative pulses of voltage are applied to the filament 10 and the electrode 12 through coupling capacitances 60 and 62, respectively, from the pulse forming circuit 47. Upon the imposition of the voltage pulses, the voltage on the electrode 12 becomes negative with respect to the voltage on the electrode 16. This causes the electrons passing through the slot 14 to be accelerated in the region between the electrodes 12 and 16 and to pass through the slot 18 into the region between the backing plate 22 and the electrode 24.

Because of the acceleration imparted to the electrons by the electrodes 12 and 16, the electrons have a considerable amount of energy as they pass through the region between the backing plate 22 and the electrode 24. This causes the electrons to strike with considerable force molecules of gas or vapor introduced into the region from the receptacle 34 and to ionize the molecules into electrons and positive ions, most of which have a single positive charge.

The ions produced from molecules of gas or vapor are retained in the electron stream because of the opposite charge of the ions relative to the charge of the electrons. Since the electron stream has a relatively large negative charge, a considerable number of ions can be retained in the stream before the stream becomes saturated. The ions are retained in a relatively confined region because of the collimating action which is provided by the slots 14 and 18 and which may be provided by a magnetic field (not shown).

When a considerable number of ions have been formed for retention in the electron stream, the electron stream is interrupted by cutting off the pulses of voltage on the filament 10 and the electrode 12. By interrupting the electron stream, the ions retained in the stream are made available for easy withdrawal from their place of retention. The withdrawal of the ions is effectuated by the imposition of pulses of voltage on the backing plate 22 and the electrode 24. These pulses of voltage are applied to the backing plate 22 and the electrode 24 through suitable coupling capacitances 64 and 66 from the pulse forming circuit 47. The pulses of voltage on the backing plate 22 and the electrode 24 may be approximately +200 and +150 volts, respectively.

Since the voltage pulse applied to the backing plate 22 is greater than the voltage pulse applied to the electrode 24, the ions are repelled by the plate 22 towards the electrode 24. The force imposed on the ions in the region between the backing plate 22 and the electrode 24 causes ions of relatively light mass to have a greater acceleration imparted to them than ions of heavy mass. The ions are further accelerated in the region between the electrodes 24 and 36 because of the voltage pulse on the electrode 24 relative to the ground potential on the electrode 36. The ions then travel through the region between the electrodes 36 and 40 at substantially the same velocities as that attained by them during their movement through the slot 38.

During their travel through the region between the electrodes 36 and 40, the ions become clearly separated on the basis of their mass. After traveling through the slot 42 in the electrode 40, the ions are attracted to the electron multiplier 44 to produce signals indicative of the relative times at which the ions of different mass reach the multiplier. The signals produced by the electron multiplier are indicated by the oscilloscope 46.

The imposition of the particular voltage pulses on the backing plate 22 and the electrode 24 provides a compensation for the differences in the positioning and in the random motion of individual ions during the time that the ions are retained in the electron stream. The differences in positioning of individual ions result from the fact that the electron stream has a finite width. The differences in the random motion of the individual ions are produced as a result of thermal and other energy in the ions. Because of the differences in random motion, some of the ions are traveling towards the backing plate 22 and other ions are traveling towards the electrode 24 at the instant that they are accelerated towards the electrode. By providing a compensation for the differences in positioning and random motion of individual ions, a relatively sharp delineation between ions of different masses is obtained. The compensation provided by the imposition of the particular voltage pulses on the plate 22 and the electrode 24 is fully disclosed in co-pending application Serial No. 249,318 filed October 2, 1951, by William C. Wiley, now Patent No. 2,685,035 issued July 27, 1954.

One embodiment of the electron multiplier 44 shown in Figure 1 is illustrated in detail in Figures 2 and 3. The electron multiplier includes a plurality of plates such as plates 80, 82, 84, 86, 88 and 90. The plates are disposed in lateral relationship to each other such that the right extremity of each plate as shown in Figures 2 and 3 is contiguous to the left extremity of an adjacent plate.

The plate 80 is further away from the electrode 40 than any of the other plates, and each of the successive plates is disposed at a progressively closer distance to the electrode 40. The plates 80, 82 and 84 are disposed in front of the slot 42 in the electrode 40 to receive different lateral portions of each ion pulse that travels through the slot.

The plates 82 and 84 have substantially equal lateral dimensions but the plate 80 has a lateral dimension somewhat greater than that provided for the plates 82 and 84. The plate 80 is disposed so that its right lateral portion is out of alignment with the slot 42 in the electrode 40. In this way, the plate 80 receives a lateral portion of the ion pulse substantially equal to the lateral portions received by the plates 82 and 84. The plate 80 also receives at its right extremity the ions deviating from a straight course at the right fringe of each ion pulse.

The plates 86, 88 and 90 are disposed to the left of the slot as seen in Figure 2 so as not to receive any portion of the ion pulses traveling through the slot 42. A plate 92 has a first portion disposed directly behind the plate 90 and substantially in alignment with the electrode 40. The plate also has a second portion extending integrally from the first portion in a direction substantially perpendicular to the first portion and at a position to the left of the plate 90.

A negative voltage of relatively large magnitude is applied to the plate 80 through a resistance 94 from a suitable high voltage power supply 96. Negative voltages of progressively decreasing magnitudes are applied to successive plates in the plurality in accordance with the distance between each plate and the electrode 40. In this way, an electric field of substantially constant magnitude is produced between the electrode 40 and each of the plates 80, 82, 84, 86, 88 and 90. The plate 92 is maintained at substantially ground potential in its steady state operation because of its connection to a grounded resistance 98.

As a typical example, each of the plates 80, 82, 84, 86, 88 and 90 may be made from a suitable material such as beryllium copper having approximately 2% by weight of beryllium. The plate 80 may be approximately 0.7" long as measured from right to left in Figure 2, and each of the other plates may have a length of approximately 3/8" in this direction. The height of each of the plates 80, 82, 84, 86, 88 and 90 as seen in Figure 2 may be approximately 1".

The plate 82 may be approximately 0.006" closer to the electrode 40 than the plate 80, and the plate 84 may be a corresponding distance closer to the electrode 40 than the plate 82. In like manner, the plates 86, 88 and 90 may be respectively closer to the electrode 40 than the plates 84, 86 and 88 by distances of approximately 0.022".

A voltage of approximately -4800 volts may be applied to the plate 80 from the power supply 96, and voltages of approximately -4750 and -4700 volts may be applied to the plates 82 and 84, respectively. Voltages of approximately -4525, -4350 and -4175 volts may be respectively applied to the plates 86, 88 and 90. Although each of the plates 80, 82, 84, 86, 88 and 90 has a different voltage applied to it, a substantially constant electric field is produced between the electrode 40 and the plates because of the differences in distance between the electrode 40 and the plates.

In the above example, a magnetic field of approximately 340 Gauss may be produced by field poles 100 in the region between the electrode 40 and the plates 80, 82, 84, 86, 88 and 90. The magnetic field is produced in a vertical direction substantially parallel to the faces of the plates 80, 82, 84, 86, 88 and 90.

Different lateral portions of each ion pulse traveling through the slot 42 impinge on the plates 80, 82 and 84. For example, the right lateral portion of each ion pulse

as seen in Figure 2 impinges on the plate 80. Because of the material from which the plate 80 is made, electrons are emitted from the surface of the plate when the ions impinge on the plate. The number of electrons emitted by the plate 80 is proportional to the number of ions reaching the plate.

The electrons emitted from the plate 80 travel in a cycloidal path towards the plate 82 because of the combined action of the electric field between the electrode 40 and the plates and the magnetic field between the field poles 100. The cycloidal path in which the electrons travel after leaving the plate 82 is illustrated at 102 in Figure 3.

At substantially the end of the cycloidal movement, the electrons impinge on the plate 82. The electrons impinge on the plate 82 with a sufficient force to cause electrons to be emitted by the plate. For reasons which will be disclosed in detail hereinafter, the number of electrons emitted by the plate 82 is substantially equal to the number of electrons impinging on the plate. Because of the particular voltages imposed on the plates 80 and 82 and the particular strength of the magnetic field, the electrons emitted by the plate 82 are in turn subjected to a cycloidal movement.

25 The 1:1 ratio between the number of electrons impinging on the plate 82 and the number of electrons emitted by the plate is produced because of the voltage difference between the plates 80 and 82. On the basis of empirical studies, for example, a 1:1 ratio is produced when the 30 plates 80 and 82 have a composition of 2% beryllium copper and a voltage difference of approximately 50 volts.

Since the plate 82 is positioned at an intermediate position with respect to the lateral dimension of each ion pulse 35 passing through the slot 42, it receives the ions in the middle portion of each ion pulse. Upon the impingement of these ions, the plate 82 produces a number of electrons proportionate to the number of ions impinging upon it. The proportion between the number of electrons emitted 40 by the plate 82 and the number of ions impinging on the plate is substantially the same as the proportion disclosed above for the plate 80. The electrons emitted by the plate 82 as a result of the impingement of ions upon the plate travel in substantially the same cycloidal path as the electrons which are emitted from the plate 82 by the impingement of electrons from the plate 80.

In like manner, the plate 84 produces electrons when the electrons from the plate 82 impinge on it. The plate 50 84 also produces electrons when ions in the left lateral portion of each ion pulse travel through the slot 42 in the electrode 40 and impinge on the plate. The electrons emitted by the plate 84 travel in a cycloidal path towards the plate 86.

Because of the positioning of the plate 86, the plate 55 does not receive any of the ions in each ion pulse. However, the plate 86 does receive the electrons traveling towards it from the plate 84 and produces a proportionately increased number of electrons. A proportionately increased number of electrons is produced by the plate 86 60 because of the difference in voltage between the plates 84 and 86. This difference in voltage is determined empirically for each material that may be used. For example, a voltage difference of 175 volts between the plates 84 and 86 causes approximately twice as many electrons to be emitted by the plate 86 as by the plate 84 when the plates are made from 2% beryllium copper.

Similarly, the plate 88 emits a number of electrons 65 which is proportionately greater than the number of electrons traveling towards it in a cycloidal path from the plate 86, and the plate 90 in turn produces a greater number of electrons than the number that is produced by the plate 88. The electrons emitted by the plate 90 are collected by the plate 92, which produces output signals 70 dependent upon the collection of electrons.

By providing a plurality of plates, each of which emits a greater number of electrons than its immediately preceding plate, a considerable gain in signal strength can be obtained over that produced by the ions in each ion pulse. For example, it is possible to produce output signals having amplitudes substantially 1 million times as great as those produced by the ions in the ion pulse. The output signals are introduced to the oscilloscope 46 to provide a relatively sharp delineation between ions of different mass.

Even though the ions in each pulse are received by a plurality of plates such as the plates 80, 82 and 84, output signals are produced which accurately indicate the relative abundance of the different ions in the pulse. Accurate signals are produced because the electrons emitted by the plate 80 travel to the plate 82 and cause substantially the same number of electrons to be emitted by the plate 82. A similar 1:1 ratio exists at the plate 84 between the number of electrons traveling towards the plate and the number of electrons emitted by the plate. In this way, the plate 84 produces a number of electrons corresponding to that which would have been produced if all of the ions in each pulse impinged on the plate.

By employing a plurality of plates to receive different lateral portions of each ion pulse, the length of each of the plates 80, 82, and 84 as measured in a horizontal direction in Figures 2 and 3 can be maintained at a relatively moderate value. Since the lengths of the plates 86, 88 and 90 have to correspond substantially to the lengths of the plates which receive the ions, such as the plates 80, 82 and 84, the plates 86, 88 and 90 can also have moderate lengths. In this way, the overall length of the electron multiplier is maintained within reasonable limits without any material sacrifice in the gain produced by the electron multiplier. Because of the reduction in size, the weight of the electron multiplier is also relatively low, and its cost of manufacture is relatively inexpensive.

It should be appreciated that the time required for the electrons from each plate to travel to and impinge upon the successive plate in the plurality is in the order of 7×10^{-4} microseconds. For example, the electrons leaving the plate 80 require approximately only 7×10^{-4} microsecond to reach the plate 82. Since this period of time is considerably less than the 0.05 microsecond period required for the ions of a particular mass in each pulse to impinge on the electron multiplier, the use of a plurality of plates does not materially cloud the measurements that are obtained. Because of this, a relatively sharp delineation is provided by the mass spectrometer between ions of adjacent mass units.

It should be appreciated that the electron multiplier disclosed above can be used in other apparatus than mass spectrometers to amplify the signals produced by an ion beam. Actually, the electron multiplier can be used with any apparatus which produces a stream of discrete particles. Such particles may have no charge or may have a positive or negative charge. The positively charged particles may include ions and the negatively charged particles may include electrons. For example, the electron multiplier may be used in conjunction with nuclear equipment to detect and amplify the signals produced by atoms, neutrons or electrons.

Although this invention has been disclosed and illustrated with reference to particular applications, the principles involved are susceptible of numerous other applications which will be apparent to persons skilled in the art. The invention is, therefore, to be limited only as indicated by the scope of the appended claims.

What is claimed is:

1. A mass spectrometer, including, means for providing a plurality of ions, means for accelerating the ions in a lateral beam to produce a separation of the ions on the basis of their mass, a first plurality of plates, each of the plates in the first plurality being disposed to collect a different lateral portion of the ion beam and to produce

a plurality of electrons substantially the same proportion to the number of ions collected as produced by the other plates in the first plurality, means for moving the electrons produced by each of the plates in the first plurality towards successive plates in the first plurality to produce in each successive plate a number of electrons substantially the same as the number of electrons received by each plate, a second plurality of plates, each of the plates in the second plurality being adapted to receive the electrons produced by a preceding plate and to produce a proportionately increased number of electrons, the first plate in the second plurality being adapted to receive the electrons traveling from the plates in the first plurality, and means for indicating the relative times at which electrons are produced by the last plate in the second plurality.

2. A mass spectrometer, including, means for producing a plurality of ions, means for accelerating the ions in a lateral beam to produce a separation of the ions on the basis of their mass, first and second series of plates disposed in lateral relationship to one another, each of the plates in the first series being disposed to collect a different portion of the ion beam and to produce a number of electrons in substantially the same proportion to the number of ions collected as are produced by the other plates in the first plurality, means operative on the plates in the first and second series to produce a cycloidal movement of the electrons emitted by each plate towards the next plate in the series, each of the plates in the first series being adapted to receive electrons from a preceding plate and to produce substantially the same number of electrons as are received by the plates, each of the plates in the second series being adapted to receive the electrons from a preceding plate and to produce a proportionately increased number of electrons, a first plate in the second series being adapted to receive the electrons traveling from the plates in the first series, and an indicator for determining the relative times at which electrons are produced by the last plate in the second series.

3. A mass spectrometer, including, means for providing a plurality of ions, means for accelerating the ions longitudinally in a beam having a substantially finite lateral dimension, a plurality of plates disposed in lateral relationship to one another and in a progressively longitudinal relationship, first plates in the plurality being disposed to receive different lateral portions of the ion beam and to produce a number of electrons proportionate to the number of ions in the beam portion, each of the first plates being adapted to receive the electrons from a preceding one of the first plates and to produce substantially the same number of electrons that it receives, second plates in the plurality being adapted to receive electrons from a preceding plate in the plurality and to produce a proportionately increased number of electrons, and an indicator for providing a determination of the relative times at which electrons are produced at the last of the plates in the second plurality.

4. A mass spectrometer, including, means for providing a plurality of ions, means for accelerating the ions in a lateral beam to produce a separation of the ions on the basis of their mass, a first plurality of plates arranged in staggered relationship to one another to receive different lateral portions of the ion beam and to produce at each plate a plurality of electrons in the same proportion to the number of ions received as are produced at the other plates in the first plurality, each plate in the first plurality being disposed relative to an adjacent plate to receive the electrons produced by an adjacent plate and to produce substantially the same number of electrons as are received, a second plurality of plates arranged in staggered relationship to one another, the first plate in the second plurality being disposed relative to the last plate in the first plurality to receive the electrons produced by the last plate and to produce a proportionately increased number of electrons, each of the other

plates in the second plurality being disposed to receive the electrons produced by a preceding plate in the plurality and to produce a corresponding number of electrons, and means for indicating the relative times at which electrons are produced by the last plate in the second plurality.

5. A mass spectrometer, including, means for providing a plurality of ions, means for accelerating the ions in a lateral beam to produce a separation of the ions on the basis of their mass, a first plate disposed to receive the ions traveling in a first lateral portion of the beam after the travel of the ions through a relatively great distance and to produce a plurality of electrons in a first proportion to the number of ions received by the plate, a second plate disposed to receive the ions in a second lateral portion of the beam and to produce a plurality of electrons in substantially the first proportion to the number of ions received by the plate, the second plate being disposed relative to the first plate to receive the electrons emitted by the first plate and to produce substantially the same number of electrons as are received, a third plate disposed relative to the second plate to receive the electrons from the second plate and to produce an increased number of electrons, and means for producing signals in accordance with the relative times at which electrons are received by the third plate to indicate the relative mass and abundance of the different ions in the plurality.

6. A mass spectrometer, including, means for providing a plurality of ions, means for accelerating the ions in a lateral beam to produce a separation of the ions on the basis of their mass, a plurality of plates disposed in staggered relationship to one another, a first plate in the plurality being adapted to receive a first lateral portion of the ion beam and to produce a proportionately increased number of electrons, a second plate in the plurality being adapted to receive a second lateral portion of the ion beam and to produce a number of electrons having substantially the same proportion to the number of ions as the proportion between the number of electrons produced by the first plate and the number of ions received by the plate, the second plate being disposed relative to the first plate to receive the electrons produced by the first plate and to produce substantially the same number of electrons as are received, a third plate in the plurality being disposed relative to the second plate to receive the electrons produced by the second plate and to produce a proportionately increased number of electrons, and means for indicating the relative times at which electrons are produced by the third plate.

7. A mass spectrometer, including, means for producing a plurality of ions, means for accelerating the ions in a lateral beam to produce a separation of the ions on the basis of their mass, a plurality of plates disposed in staggered relationship to one another, a first plate in the plurality being disposed to receive a first portion of the lateral beam and to produce a plurality of electrons bearing a first proportion compared to the number of ions received by the plate, a second plate in the plurality being disposed to receive a second portion of the lateral beam and to produce a plurality of electrons bearing substantially the first proportion compared to the number of ions received by the plate, the second plate being disposed relative to the first plate to receive the electrons produced by the first plate and to produce substantially the same number of electrons as the number of electrons received by it, a third plate in the plurality being disposed relative to the second plate to receive the electrons produced by the second plate and to produce a proportionately increased number of electrons, and means for indicating the

relative times at which electrons are produced by the third plate.

8. In combination, means for providing a plurality of particles and for directing the particles in a lateral beam, a first plate disposed to receive the particles in a first lateral portion of the beam after the travel of the particles through a particular distance and to produce a plurality of electrons in a first proportion to the number of particles that it receives, a second plate disposed to receive the particles in a second lateral portion of the beam and to produce a plurality of electrons in substantially the first proportion to the number of particles that it receives, the second plate being disposed relative to the first plate to receive the electrons emitted by the first plate and to produce substantially the same number of electrons as are received by it, a third plate disposed relative to the second plate to receive the electrons emitted by the second plate and to produce a proportionately increased number of electrons, and means for producing signals indicative of the electrons produced by the third plate.

9. In combination, means for providing a plurality of particles and for directing the particles in a lateral beam, a first plate disposed to receive the particles in a first lateral portion of the beam after the travel of the particles through a particular distance and to produce a plurality of electrons in a first proportion to the number of particles it receives, a second plate disposed to receive the particles in a second lateral portion of the beam and to produce a plurality of electrons in substantially the first proportion to the number of particles it receives, means for providing an electrical field in a direction substantially perpendicular to the plates, means for providing a magnetic field in a direction substantially parallel to the plates to cooperate with the electrical field in producing a movement of the electrons emitted by each plate to a successive plate for the emission of electrons by the successive plate, the second plate disposed to receive the electrons emitted by the first plate and to produce substantially the same number of electrons as are received by it, a third plate disposed relative to the second plate to receive the electrons emitted by the second plate and to produce a proportionately increased number of electrons, and means for producing signals indicative of the electrons emitted by the third plate.

45. 10. In combination, means for providing a plurality of particles and for directing the particles in a lateral beam, a first plate disposed to receive the particles in a first lateral portion of the beam after the travel of the particles through a particular distance and to produce a plurality of electrons in a first proportion to the number of particles it receives, a second plate disposed to receive the particles in a second lateral portion of the beam and to produce a plurality of electrons in substantially the first proportion to the number of particles it receives, the second plate being disposed relative to the first plate to receive the electrons emitted by the first plate and to produce substantially the same number of electrons as are received by it, a third plate disposed relative to the second plate to receive the electrons emitted by the second plate and to produce a proportionately increased number of electrons, means for providing electrical and magnetic fields in directions to produce a movement of electrons from the first plate to the second plate and from the second plate to the third plate, and means for producing signals indicative of the electrons produced by the third plate.
